(57) **CLAIM**

The ornamental design for a reformer exercise apparatus frame, as shown and described.

DESCRIPTION

This design application is related to United States Utility patent application Ser. No. 13/181,707, entitled Reformer Exercise Apparatus.

FIG. 1 is an upper perspective view of our new reformer exercise apparatus frame design. The broken lines show portions illustrating environmental structure of the reformer frame that form no part of the claimed design.

FIG. 2 is a head end elevational view of our new reformer exercise apparatus frame design. The broken lines show portions illustrating environmental structure of the reformer that form no part of the claimed design.

FIG. 3 is a rear end elevational view of the reformer exercise apparatus shown in FIG. 1. The broken lines show portions illustrating environmental structure of the reformer that form no part of the claimed design.

FIG. 4 is a right side elevational view of the reformer exercise apparatus shown in FIG. 1. The broken lines show portions illustrating environmental structure of the reformer that form no part of the claimed design.

FIG. 5 is a left side elevational view of the reformer exercise apparatus shown in FIG. 1. The broken lines show portions illustrating environmental structure of the reformer that form no part of the claimed design.

FIG. 6 is a top plan view of the reformer exercise apparatus shown in FIG. 1. The broken lines show portions illustrating environmental structure of the reformer that form no part of the claimed design; and,

FIG. 7 is a bottom plan view of the reformer exercise apparatus shown in FIG. 1. The broken lines show portions illustrating environmental structure of the reformer that form no part of the claimed design.
